UNITED STATES PATENT OFFICE.

ARCHIBALD HASTIE DICK, OF SCHENECTADY, NEW YORK.

SPARK-ARRESTER.

1,322,768.

Specification of Letters Patent. Patented Nov. 25, 1919.

Application filed May 3, 1917. Serial No. 166,255.

To all whom it may concern:

Be it known that I, ARCHIBALD H. DICK, a subject of the King of Great Britain and Ireland, who have declared my intention to 5 become a citizen of the United States, am a resident of Schenectady, in the county of Schenectady and State of New York, temporarily residing at Rio de Janeiro, Brazil, and have invented certain new and useful 10 Improvements in Spark-Arresters, of which the following is a specification.

This invention relates primarily to front end arrangements for locomotives, and more specifically to a spark arrester of the rotary 15 type.

It has heretofore been proposed to place a rotary cylindrical screen in the space between the exhaust nozzle and the stack of a locomotive, and to rotate it by the exhaust 20 blast. (See for example, the U. S. patent to Saccaggio and Lagrange No. 1,125,727). All such prior devices, have, so far as I am aware, been subject to the serious disadvantage that the supporting and driving mechanism was in the direct path of the entire 25 exhaust blast. This mechanism by breaking and deflecting the main jet of exhaust steam seriously impairs ejector action of the steam jet and causes an undesirable reduction of 30 draft.

Consequently, one of the important objects of the present invention is the provision of a type of supporting and driving mechanism which shall deflect only a small 35 portion of the jet, leaving the main central portion of the jet to pursue its normal course. This result is secured by using annular bearings, in combination with an annular peripheral turbine formed partly on 40 the exhaust nozzle, said bearings and the fluid passages of the turbine encircling and being concentric with the central portion of the jet. This operates efficiently with only a small proportion of the exhaust steam, 45 and the remaining central portion of the jet is unimpaired either in velocity or direction. The said turbine may be operated either with live steam or exhaust steam, or a combination of both live steam and exhaust 50 steam.

Other features of the invention relate to special forms and arrangements of parts

such as the turbine rotor, screen, etc., and will be readily understood by those skilled in the art, from the following description 55 and from the accompanying drawings, in which—

Figure 1 is a vertical axial section through the screen mechanism together with portions of the exhaust pipe and smoke stack 60 extension;

Fig. 2 is a vertical section through so much of the front end of a locomotive as is necessary to show the location and arrangement of my invention when used on a locomotive;

Fig. 3 is a section on the line 3—3 of Fig. 1;

Fig. 4 is a plan view of the turbine rotor;

Fig. 5 is a section on the line 5—5 of 70 Fig. 4;

Fig. 6 is a plan view of the exhaust nozzle;

Fig. 7 is a section on the line 7—7 of 75 Fig. 6;

Fig. 8 is a section on the line 8—8 of Fig. 6.

In the drawings, 9 is the exhaust pipe leading from the exhaust passages in the saddle and 10 is the exhaust nozzle casting 80 which is connected to the exhaust pipe 9 by studs or bolts as shown, but may be made in one piece therewith. An interchangeable thimble or bush 11, is provided for the nozzle 10 and is held by studs 12. The 85 form of the thimble 11 may be varied to adjust the exhaust jet to the requirements of any particular service, and this makes relatively simple the standardization of the nozzle 10 in a relatively small number of different sizes.

The nozzle 10 has, in addition to the central orifice which carries the bushing 11, an annular series of apertures 13 which serve 95 as turbine nozzles and conduct a relatively small quantity of exhaust steam to the turbine rotor 14. One or more of this series of apertures 13 may be utilized to conduct a relatively small quantity of live steam to the turbine motor. This live steam supply may be regulated in any convenient manner, preferably by means of an ordinary valve in the live steam supply pipes 29. The rotor 14 is 100 a ring-shaped casting having oblique blades

or buckets 15 in the path of steam issuing from the nozzle 10. In the particular example illustrated the nozzles 13 are shown as outwardly flaring passages and the buckets 15 as simple oblique blades. These forms are ordinarily sufficient, but where it is desired to reduce the consumption of steam any of the various scientific designs of nozzle and bucket may be used with good effect.

10 The rotor 14 in the preferred form turns in contact with a bearing plate 16 fast on the top of nozzle 10, and a thrust plate 21 secured to nozzle 10 by studs or bolts 12, and is free to revolve thereon. It is held centered by a depending flange 17 running in a groove 18 formed in nozzle casting 10. In some cases it will be found desirable to provide the groove 18 with balls 19, and to place balls 20 over flange 17, thus making 20 the rotor of a ball bearing type as illustrated in Fig. 1. When ball bearings are used the plate 21 may be made in one piece with nozzle bushing 11, and the bearing plate 16 may be omitted.

25 The screen structure consists of a cylindrical screen secured to conical base plate 23, to the outer flange of rotor casting 14, and to the top ring 24 by either bolts or rivets. The top ring 24 is constructed of a circular 30 plate 24 and angle irons 25, and is free to move around a depending portion 26 of the smoke stack 27.

While the screen members 22, 23, and 24 may be of any foraminous material such as 35 netting or various forms of perforated plate, I show and prefer screen 22 of netting, base plate 23 and top ring 24 of plate.

An ordinary petticoat pipe 28 may be used in combination with this device if desired.

Deflecting plates 30 may be used if desired when it is necessary to increase the speed of the gaseous products of combustion through netting 22. The preferred 45 arrangement as illustrated shows the deflecting plates 30 bolted to rotor casting 14, but they may be fastened to screen 22 either on the inside or outside of screen 22.

The invention is shown in Fig. 2 mounted in a locomotive smoke box, that being the usual but not the exclusive field of use for the device. The blast of the exhaust creates a draft out through the stack in the usual manner and a part of the exhaust, which 55 may be assisted by live steam from the boiler, rotates the screen which is in the path of products of combustion passing to the stack. As the screen moves faster than the cinders they are thrown back into the 60 smoke box and out of the line of draft. Small sparks are beaten out or extinguished. The screen thus arrests and extinguishes sparks and is self clearing. The deflecting plates convey the products of combustion 65 from the screen to the center of the exhaust

jet where they are ejected out of the stack in the usual way. The deflecting plates also serve the purpose of beating out any relatively small sparks which might find their way through holes in the screen. The device offers little obstruction to the draft and does not retard or deflect the draft-creating blast in any substantial degree.

70 The possibility of certain modifications has been suggested and others will be obvious to skilled mechanics. The important feature is the provision of means for supporting and driving a screen of this type, without substantial interference with the exhaust blast. So far as the feature of support is concerned, it is not even essential that the turbine be of the exhaust, or live, steam variety.

75 It will be observed that under the above described construction and as plainly illustrated in the drawings, the space between the discharge end of the exhaust nozzle 10 and the smoke pipe or petticoat pipe 28 is wholly unobstructed, and no impediment of any sort obstructs the exhaust. The deflecting plates 30 as will be seen upon reference to Figs. 1 and 3, lie wholly outside the circumference of the outlet or central discharge opening of nozzle 10, and in planes 80 parallel with the axis of rotation of the screen though tangential thereto. In other words, they lie in vertical planes and not in planes oblique to the axis of rotation, hence afford free vertical passage for the exhaust throughout the area of the rotating screen, 85 thus avoiding radial arms, fan blades, and the like, movable across the path of the exhaust. This conduces greatly to the efficiency of the structure and is an important 90 feature of the invention.

95 Having thus described my invention, what I claim is:

1. The combination of an exhaust nozzle; a smoke flue alined therewith and spaced therefrom; a rotatable tubular screen, having an unobstructed interior, bridging the interval between said nozzle and flue; bearings for said tubular screen; and a motor for rotating said screen.

110 2. The combination of an exhaust nozzle; a smoke flue alined therewith and spaced therefrom; a rotatable tubular screen, having an unobstructed interior, bridging the interval between said nozzle and flue; bearings for said tubular screen; and a motor operable by exhaust steam for rotating said screen.

115 3. The combination of an exhaust nozzle; a smoke flue alined therewith and spaced therefrom; a rotatable tubular screen, having an unobstructed interior, bridging the interval between said nozzle and flue; bearings for said tubular screen; and a motor operable by live steam from any source for 120 rotating said screen.

4. The combination of an exhaust nozzle, a smoke flue alined therewith and spaced therefrom, a rotatable tubular screen, having an unobstructed interior, bridging the 5 interval between said nozzle and flue; bearings for said tubular screen; and a turbine including nozzles in said exhaust nozzle and buckets on said screen for operating said screen by exhaust steam from said exhaust 10 nozzle.
5. The combination of an exhaust nozzle, a smoke flue alined therewith and spaced therefrom; a rotatable tubular screen, having an unobstructed interior, bridging the 15 interval between said nozzle and flue; bearings for said tubular screen; and a turbine motor operable by a combination of exhaust steam from said exhaust nozzle and an auxiliary supply of live steam from any source.
- 20 6. The combination of an exhaust nozzle having a main central exhaust opening, and one or more lateral turbine nozzle openings; a flue alined with said central exhaust opening and spaced from said exhaust nozzle; a 25 rotatably mounted tubular screen bridging the interval between said nozzle and flue; and a turbine rotor connected with said screen and having buckets in coactive relation with said turbine nozzles.
- 30 7. The combination of an exhaust nozzle, having a main central exhaust opening, and a surrounding annular series of turbine nozzles; a flue alined with said central exhaust opening and spaced from said exhaust 35 nozzle; a rotatably mounted tubular screen bridging the interval between said nozzle and flue and inclosing said turbine nozzles and central exhaust opening; and an annular series of turbine buckets mounted on the 40 inside of said screen in coactive relation with said turbine nozzles and out of the path of steam from said central exhaust opening.
8. The combination of an exhaust nozzle 45 having a main central exhaust opening, a surrounding annular series of turbine nozzles, and an annular bearing; a flue alined with said central exhaust opening and spaced from said exhaust nozzle; an annular 50 turbine rotor mounted on said annular bearing and having a series of buckets in coactive relation with said nozzles but out of the path of steam from said central exhaust opening; a tubular screen rigidly mounted on said rotor and bridging the 55 interval between said exhaust nozzle and flue; and a thrust bearing for said rotor.
9. The combination of an exhaust nozzle 60 having a main central exhaust opening, a surrounding annular series of turbine nozzles, and an annular bearing; a flue alined with said central exhaust opening and spaced from said exhaust nozzle; an annular turbine rotor mounted on said an-
- nular bearing and having a series of buckets 65 in coactive relation with said nozzles but out of the path of steam from said central exhaust opening; a tubular screen rigidly mounted on said rotor outside said buckets and bridging the interval between said exhaust nozzle and flue; and a thrust bearing 70 for said rotor.
10. The combination of an exhaust nozzle having a main central exhaust opening, a surrounding annular series of turbine nozzles, and an annular bearing; a flue alined with said central exhaust opening and spaced from said exhaust nozzle; an annular turbine rotor mounted on said annular bearing and having a series of buckets 75 in coactive relation with said nozzles but out of the path of steam from said central exhaust opening; a tubular screen rigidly mounted on said rotor and bridging the interval between said exhaust nozzle and flue; and a thrust bearing for said rotor serving to hold the rotor to its seat.
11. A removable exhaust nozzle and spark arrester unit, adapted to be interposed between the exhaust pipe and stack of a locomotive, and comprising in combination an exhaust nozzle provided with attaching means, a central exhaust opening, and lateral turbine nozzles; a rotary tubular screen journaled on said exhaust nozzle and having turbine buckets coacting with said turbine nozzles; and a thrust bearing for said screen.
12. A removable exhaust nozzle and spark arrester unit, adapted to be interposed between the exhaust pipe and stack of a locomotive, and comprising in combination an exhaust nozzle provided with attaching means, a central exhaust opening, and lateral turbine nozzles; and a rotary tubular screen journaled on said exhaust nozzle and having turbine buckets coacting with said turbine nozzles, said screen having at its 90 top a collar loosely encircling a depending portion of the stack.
13. A removable exhaust nozzle and spark arrester unit adapted to be interposed between the exhaust pipe and stack of a locomotive, and comprising in combination an exhaust nozzle provided with attaching means, a central exhaust opening and an annular series of turbine nozzles surrounding said central exhaust opening; and a rotary tubular screen journaled on said exhaust nozzle and having on its inner side a 95 plurality of turbine buckets in coactive relation with said turbine nozzles and out of the path of steam from said central exhaust opening; said screen having at its top a collar loosely encircling a depending portion of the stack.
14. The combination of an exhaust nozzle, a smoke flue alined therewith and spaced

therefrom; a rotatable tubular screen, having an unobstructed passage for the exhaust blast, bridging the interval between said nozzle and flue; peripheral bearings for said tubular screen; and deflecting plates attached to said tubular screen for the purpose of conducting the products of combus-

tion passing through said screen to the center of the exhaust blast; and a motor for rotating said screen.

In testimony whereof I have signed my name to this specification.

10

ARCHIBALD HASTIE DICK.
